UNITED STATES PATENT OFFICE.

HERMANN RAHN, OF CHARLOTTENBURG, GERMANY

APPARATUS FOR SHAPING METAL ARTICLES.

1,023,962.

Specification of Letters Patent.

Patented Apr. 23, 1912.

Application filed February 8, 1912. Serial No. 676,375.

To all whom it may concern:

Be it known that I, HERMANN RAHN, a citizen of the Empire of Germany, and residing at Charlottenburg, near Berlin, Germany, have invented certain new and useful Improvements in Apparatus for Shaping Metal Articles, of which the following is a specification.

My invention relates to apparatus for shaping metal articles.

The shaping of thin rotating bodies, for example disks, by pressure has heretofore been done by the operator securely holding the tool freely on a support. When the disks are large the operator must support himself firmly against a prop connected with the lathe. This known process has important defects attached to it. It is very slow and involves the exertion of great bodily force. Also, great skill is necessary. Even this, however, does not protect the operator from injury particularly because in the customary process his free left hand must guide a support and prevent the outer edge of the work-piece from vibrating too severely before it bears on the former; scars due to serious injuries of this hand are therefore considered, as it were, characteristic of the calling. Further, on account of the danger connected with it, work-pieces bulged out of shape cannot be worked up further.

Now a primary object of my invention is to provide an improved process and apparatus for carrying the same into practice to which these defects are not attached.

To this end, my invention substantially consists in using two two-armed levers, the one provided with the tool and freely guided being used for shaping the work-piece, while the second exercises the requisite pressure independently of the first. The lever carrying the tool can thus be guided along the work-piece substantially independently of the second lever. This independent adjustability of the tool-lever makes the apparatus characteristically different from apparatuses known heretofore in spinning machines.

In order to enable my improved process to be executed by only one operator, according to my invention I provide for the work-

piece a mechanical support in the form of a spring-pressed roller or the like so that, in contradistinction to the well-known processes, the left hand of the operator is free for guiding the second lever.

55

Some illustrative embodiments of my invention and modifications thereof are represented by way of example in the accompanying drawing, wherein:

Figure 1 is a top plan view showing part 60 of a lathe, partly in section, a single pair of two-armed levers, and the support provided according to the invention for the outer edge of the work-piece; Fig. 2 is a like view showing a modified form of a pair of levers 65 only, the end of the presser-lever being formed as a disk, Fig. 3 a section taken on the line E—F in Fig. 2 through the presser-lever and the disk portion thereof, and Fig. 4 a side elevation of the tool-lever shown in 70 Fig. 2; Fig. 5 is an elevation of part of a tool-lever specially adapted for shaping soft metal, and Fig. 6 is a like view of a modified form of the lever shown in Fig. 5.

Referring firstly to Fig. 1, the simplest 75 apparatus for carrying my process into practice is here shown. *a* designates the presser-lever fulcrumed on a pivot *e* secured in a rest *n* firmly connected with the frame *D* of the lathe indicated by cross-hatching. *e* 80 designates the tool-lever carrying at its one end the tool *w* which may have the form of a roller as shown in the drawing. It is as universally revoluble as possible, it being rotatable about a pivot *j* mounted revolubly in the pressure lever *a* as in a universal joint. Each lever is provided with a handle *f*. The other parts shown in the figure illustrate how the improved apparatus is used. *u* is the former or die. It 90 is driven by a grooved pulley *b* which is fast on the shaft *L* carrying the former *u* and journaled in the frame *D*. *s* designates the work-piece, a thin sheet of metal held by nuts *t* in front of the former *u*. *p* designates the support, provided according to my invention, for supporting the work-piece 95 at its outer edge. It is movably mounted in a bearing *q* provided on the frame *D* and is under the action of a spring *r*.

100

The arrangement according to Fig. 2 is for rendering the improved process capable of being employed in as many ways as possible. Here a' g designate the presser-lever 5 which is formed at its end serving for guiding the tool-lever e as a disk g which, in the illustrative embodiment, is a circular eccentric and is provided both with holes i for receiving the pivot j of the tool-lever e , and 10 also with screw-threaded holes k for receiving the part a' (Fig. 3). This arrangement enables not only the presser-tool to be guided along the work-piece s in any required curve, and the magnitude of the pressure to be made 15 greater or less at any moment independently of the guiding of the tool, but also the ratio of transmission at the presser-lever to be varied considerably. For the latter purpose the holes i for the pivot of the tool-lever are 20 provided at various distances from the center of rotation h of the eccentric disk g .

Fig. 4 shows the tool-lever e provided with a number of notches or recesses m . It requires to be only loosely rested on the 25 pivot l in the fork d . This has two advantages: Firstly, not only can changes in the ratio of transmission be made at the tool-lever, but also, which is perhaps more important, changes in length between the 30 work-piece and the fulcrum l of the tool-lever can likewise be made with the greatest ease, and, secondly, the apparatus is considerably safer in working because should the tool w unexpectedly catch in the work-piece 35 the tool-lever e will generally rise from the pivot l without causing any damage.

In Fig. 5 is shown a tool-lever in which the recesses m just described have the form of annular grooves o concentric with the 40 axis of the lever. Also the lever e is provided with a tool v which, in contradistinction to the roller w shown in Figs. 1, 2 and 4, is firmly connected with the lever e and thus can not move relatively thereto. Such 45 tool-levers can be arbitrarily rotated about the axis of the tool or by the friction on the work-piece. They are requisite for working soft sheet-metal, *e. g.* of brass, copper, tin. The tool v is preferably exchangeably 50 mounted in the lever e , as indicated by the cotter y in the drawing, so that the lever e solely serves as a tool holder. Both grooves and notches may, of course, be provided in one and the same lever, and the same 55 lever may be adapted by means of a slot in the head x for tools of the type of the roller w , as indicated by the slot z in Fig. 6. The arrangement according to Fig. 6 is accordingly that of a universal presser-tool.

60 I claim:—

1. In apparatus for shaping thin rotating metal bodies by pressure, the combination with a frame for carrying the rotating body

to be shaped, of a suitably supported manual presser lever and a manually guided tool 65 lever fulcrumed on the presser lever.

2. In apparatus for shaping thin rotating metal bodies by pressure, the combination, with a frame for carrying the rotating body to be shaped, of a manual presser-lever comprising a handle at one end and a disk portion at the other fulcrumed on the frame, the fulcrum of the presser-lever being located within the periphery of the said disk, and a manually guided tool-lever fulcrumed 75 on the said disk.

3. In apparatus for shaping thin rotating metal bodies by pressure, the combination, with a frame for carrying the rotating body to be shaped, of a manual presser-lever comprising a handle at one end and a disk portion at the other fulcrumed on the frame, the fulcrum of the presser-lever being located within the periphery of the said disk, the said disk having a plurality of 80 holes at various distances from the fulcrum of the presser-lever, and a manually guided tool-lever detachably and exchangeably fulcrumed in one of the holes in said disk.

4. In apparatus for shaping thin rotating metal bodies by pressure, the combination with a frame for carrying the rotating body to be shaped, of a suitably supported manual presser lever and a manually guided tool lever readily detachably fulcrumed on 95 the presser lever.

5. In apparatus for shaping thin rotating metal bodies by pressure, the combination, with a frame for carrying the rotating body to be shaped, of a manual presser-lever fulcrumed on the frame, a pivot rotatably mounted on the presser-lever, and a recessed, manually guided tool-lever fulcrumed on said pivot, said pivot entering 100 into a recess in the tool-lever.

6. In apparatus for shaping thin rotating metal bodies by pressure, the combination, with a frame for carrying the rotating body to be shaped, of a manual presser-lever fulcrumed on the frame, a pivot rotatably mounted on the presser-lever, and an axially concentrically grooved, manually 110 guided tool-lever fulcrumed on said pivot, said pivot entering into a groove in the tool-lever.

7. In apparatus for shaping thin rotating metal bodies by pressure, the combination, with a frame for carrying the rotating body to be shaped, of a manual presser-lever fulcrumed on the frame, a manually guided tool-lever fulcrumed on the presser-lever, and a tool detachably mounted in the end of the tool-lever.

8. In apparatus for shaping thin rotating metal bodies by pressure, the combination 125 with a frame for carrying the rotating body

to be shaped and a suitably mounted elastic support for supporting the free edge of the rotating body against vibration, of a suitably supported manual presser lever and a 5 manually guided tool lever fulcrumed on the presser lever.

In testimony whereof, I have signed my

name to this specification in the presence of two witnesses.

HERMANN RAHN.
